Patented Apr. 20, 1976

239,663

MINIATURE STEAM CURLING IRON

Douglas A. Long, 94 Sturges Ridge Road, Wilton, Conn. 06897, and Frederick A. Burke, 40 Riverside Ave., Riverside, Conn. 06878

Filed Dec. 26, 1974, Ser. No. 536,707

Term of patent 14 years

Int. Cl. D28—03

U.S. Cl. D86—10 E

FIG. 1 is a side perspective view of a miniature steam curling iron showing our new design;

FIG. 2 is a side elevational view of the opposite side of FIG. 1;

FIG. 3 is a top plan view;

FIG. 4 is a bottom plan view;

FIG. 5 is a front end elevational view; and

FIG. 6 is a back end elevational view thereof.

We claim:

The ornamental design for a miniature steam curling iron, as shown and described.
